UNITED STATES PATENT OFFICE

ROBERT KINGSLEY HOPKINS, OF NEW YORK, N. Y., ASSIGNOR TO THE M. W. KELLOGG COMPANY, A CORPORATION OF DELAWARE

METHOD OF AND MEANS FOR FORMING FLANGED ARTICLES

Application filed September 29, 1927. Serial No. 222,786.

The present invention relates to a process of, and apparatus for, forming flanged articles, and in particular to the forming of annular flanges with hubs.

In forming flanged articles, and particularly where the flanged portion is relatively wide and the ratio of the thickness of the body of the article to that of the flanged portion is large, the methods heretofore employed have required recourse to considerable machining work to bring the article down to finished dimensions. This is due to the fact that there is an unequal distribution of metal between the flanged portion and the body portion, and in following any of the methods heretofore proposed for reducing the section of the blank both in the flanged portion and the body portion by rolling or forging it has not been possible to bring about the elongation of the respective portions at the same rate. This is particularly true when rolling annular flanges having high hub portions and where the ratio of the flange thickness to the hub thickness is large.

According to the present invention the flanged article, such for example, as an annular flange having a high hub portion, is rolled in such a way that the hub and the flanged body elongate at the same rate; that is to say, the percentage of reduction of each is the same. In this way an article rolled to its finished dimensions may be produced. Also by causing the various portions of the article to "grow" proportionally, the setting up of undesirable stresses in the metal is avoided.

The invention also includes a roll of special construction and means for associating it with rolls of more or less standard construction in such a way as to carry out the method above described.

In the drawings:

Fig. 1 is a section through an annular billet of a type suitable for use in rolling flanges.

Fig. 2 is a section showing the billet illustrated in Fig. 1 after it has been rolled according to the practice heretofore employed and with the dimensions of the finished flange indicated in dotted lines.

Fig. 3 shows a section of a billet similar to that shown in Fig. 1, together with a representation, superimposed thereon in dotted lines, of the flange at the end of the rolling operation, and also showing the position the roll occupies at the beginning of the rolling operation and its course during the period in which the billet is being reduced to a flange of the desired dimensions.

Fig. 4 is similar to Fig. 3 except that a billet with a hub is shown.

Fig. 5 is a side elevational view of an apparatus embodying the present invention with a blank shown in section and in position to be rolled.

Fig. 6 is a side elevational view of a modified form of apparatus with a blank shown in section in position to be rolled similarly as in Fig. 5.

Fig. 7 is a top plan view of the apparatus shown in Fig. 5.

Fig. 8 is a perspective view showing the roll assembly being used in rolling straight flanged sections.

Fig. 9 is a side elevational view of a further modification of the roll assembly including a modified form of the roll which constitutes one of the characteristic features of the present invention.

Fig. 10 is a side elevational view of a roll assembly embodying still another form of the improved roll construction, and

Fig. 11 is a side elevational view of still another form of roll assembly embodying features of the present invention.

In the drawings, Figs. 1 and 2 illustrate a type of billet used, and a rolling procedure that has heretofore been followed, in forming flanges. According to this prior practice a thick billet or "biscuit" 20 is rolled in a mill having the axes of the rolls parallel to the axis of the flange and with the feed taken in a direction normal to the axis as in a tire mill. The resulting product 21 will assume a shape substantially as shown in Fig. 2, and still requires considerable machining to produce the finished flange which is indicated by dotted lines at 22. The portion which must be machined away in order to produce the finished flange is indicated at 23.

As above indicated, the reason the billet is not rolled with a hub more nearly approximating the finished hub is because of the unequal distribution of the metal. This could not be done even though the cast billet had a hub on it. Suppose, for instance, it was attempted to roll a high hub flange by the present process from either a flat billet as shown in Fig. 1 or from a billet with a hub.

It is quite obvious for a given bite of the rolls taken in a direction normal to the axis of the flange that the percent reduction of the flange body will be less than the percent reduction of the hub and for this reason the hub will elongate at a greater rate than the flange body. This will, of course, give a flange with a bell-mouthed hub, and if the rolling is carried far enough, one with a scalloped hub will result.

Because of this fact, it is evident, that in order to roll a flange more nearly to its finished dimension, the reductions, or bites, must be taken in such a way that the hub and flange body will elongate at the same rate; in other words, the percentage reduction on each must be the same. This is done as shown in Figs. 3 and 4.

In any flange there is a certain definite relation between hub thickness and flange thickness. If this same relation is maintained in the billet 24 such as shown in dotted line in Fig. 4 and the rolling is directed in a line *ba*, the percentage reduction on both hub 25 and flange body 26 will be the same and the elongation in both these members will, therefore, be identical.

Since a billet 24 as shown in Fig. 4 is quite expensive to make, it is possible to make a hub flange from a flat billet or "biscuit" 27 as shown in Fig. 3, the only requirement being that the rolling be done in the direction of the line *ba*, and that the point of the roll be placed in such an initial position that the ratio between distance *cb* and thickness of billet *ca*, shall be the same as the ratio of finished hub thickness to finished flange thickness.

This type of rolling can be accomplished on either of the machines shown in Figs. 5 and 6.

In Fig. 5 the flange receives a pure rolling action on all surfaces, while in Fig. 6 it is supported on a revolving disc 28 and is rolled against the face of this disc and also against a central projecting pin or roll 29.

The machine or roll assembly shown in Figs. 5 and 7 comprises a plurality of supporting rolls 30 and 33 which may be either driven or merely idle rolls, or partly driven and partly idle rolls. In the drawings the rolls 30 are mounted to rotate idly and the roll 33 is driven from a suitable source of power. Positioned above the roll 33 is shown still another roll 34. This roll is shaped especially for carrying out the method herein dis-

closed and has the form of a pair of truncated cones abutting at their bases and presents two rolling surfaces 35 and 36 which are shown as meeting at right angles. However, it will be understood that for producing a hub section and an abutting section on the flange which sections vary in thickness, as for example, thinner either at the outer edges or at the point of intersection of the hub and body portions on either or both of such portions, the rolling surfaces may intersect at an angle greater than or less than 90°. The roll 34 is mounted axially on a shaft 37 and may be either driven or idle. In order to simplify the apparatus it is preferred to omit mechanism for driving the roll 34. However, means are provided for adjusting the roll 34 to and from the billet or blank 38 being worked upon so as to control the bite taken or the rate of reduction. While the means for supporting and adjusting the roll 34 may assume various forms, in the drawing the shaft carrying the roll 34 is shown as mounted in bearings 39 formed in the ends of a yoke 40 which in turn is mounted on the end of a rack bar 41 which is adapted to be reciprocated in the housing 42 by means of the pinion 43 or other suitable means.

As is indicated in the drawing the roll 34 is so mounted that it follows such a path, as it is adjusted during the course of the reduction of the blank, that the point or line of intersection 45 of the rolling surfaces 35 and 36 tends to move toward the inner surface of the annular billet and to follow a straight line passing through the point or line of intersection 46 of the bottom surface and the inner surface of the annular billet or blank 38. An inner roll 47 is shown as cooperating with the rolls 33 and 34. This roll is preferably driven and may or may not be adjusted toward and away from the rolls 33 and 34. Adjustable guide rolls 48 are also provided.

In Fig. 6, in lieu of the rolls 30 and 33, a revolving disc 28 carried by a vertical shaft 49 is provided, and in lieu of the inner roll 47 a central pin 29 also mounted on the shaft 49 is provided. It will be understood, however, that instead of mounting the central pin or roll 29 on the shaft 49, it may be supported from above in any suitable manner.

In Fig. 8, a rectangular billet or blank 50 is shown as being rolled by means of the rolls 33, 34 and 47. Guide rolls 48 and supporting rolls 30 are also provided.

In the modification shown in Fig. 9, a roll similar in its principle of operation to roll 34 above described but with a plurality of double frusto-conical sections is provided. This roll in addition to having rolling surfaces meeting on the line of intersection 45 has shoulders defining surfaces 52 and 53 intersecting on the line 54 and surfaces 55 and 56 intersecting on the line 57. The surface 53 is adapted to engage the outer peripheral sur-

- face of the body of the flange being rolled and to cooperate with a shoulder 58 carried by the roll 33' in forming such peripheral surface to a finished dimension. Similarly 5 the rolling surface 55 engages the upper edge portion of the hub and cooperates with a shoulder 59 on the roll 47' to roll the upper edge portion of the hub to a finished dimension.
- 10 According to the modification shown in Fig. 10 a roll 60 is provided. This roll is similar in general form to roll 51 except that it has shoulder portions defining the surfaces 53' and 55' which portions extend outward 15 a sufficient distance to entirely close, respectively, the space between the roll 60 and the roll 33 at the outside peripheral edge of the body of the flange, and the space between the roll 47 and the roll 60 at the upper edge of 20 the hub.
- In the modification shown in Fig. 11 a roll 34 having a single double frusto-conical section is used in conjunction with rolls 33'' and 47'' having shoulder portions 58' and 59' extending outward from the body portions of the respective rolls a sufficient distance to close the spaces between the body portions of the rolls 33'' and 47'' and the opposing portions of the roll 34.
- 25 In Figs. 9, 10 and 11 the rolls and the flanges being worked are shown in the position they assume at the end of the rolling operation and at the time when the flange has been brought to its finished dimensions. It 30 will be understood that either an annular billet with a hub formed thereon or a plain annular blank or "biscuit" may be operated upon the same as in the case of the modifications previously described. Also, if desired, 35 the flange or other member being rolled may be brought substantially to its finished dimensions with a roll assembly such as shown in Figs. 5 and 6 and then transferred to a roll assembly such as any one of those shown in 40 Figs. 9, 10 and 11 and further rolled to finished dimensions. It will also be understood that the modifications shown in Figs. 9, 10 and 11 may be used in rolling rectangular billets or blanks such as shown in Fig. 8.
- 45 In Figs. 9, 10 and 11 the auxiliary supporting rolls and guide rolls have not been shown. However, it is to be understood that such rolls are provided, or other suitable means used for supporting or guiding the blank.
- 50 While the invention has been described with particular reference to the apparatus shown, it is to be understood that the method may be carried out with other forms of apparatus and that various modifications and changes in the apparatus shown and described may be made without departing from the invention. Accordingly, the invention is not deemed to be limited other than as indicated 55 in the appended claims.
- What I claim is:
1. Process of forming a metal article having an extended flange portion, in which the flange and body portions of the article are developed simultaneously and in the same proportion as these portions bear in the finished article, which comprises rolling a blank of rectangular cross section with a roll having rolling surfaces disposed at right angles and causing said roll to advance, in the course of the reduction of the blank, from a predetermined point on one surface of the blank in a path defined by a straight line passing through the line of intersection of the surfaces of said blank remote from the portion being worked on by said roll. 70
  2. Process of forming annular metal articles having a high hub portion and an extended flange portion, in which the flange and hub portions of the article are developed simultaneously and in the same proportion as these portions bear in the finished article, which comprises rolling a blank of rectangular cross section with a roll having rolling surfaces disposed at right angles and causing said roll to advance, in the course of the reduction of the blank, from a predetermined point on one surface of the blank in a path defined by a straight line passing through the line of intersection of the surfaces of said blank remote from the portion being worked on by said roll. 75
  3. Process of forming annular metal articles having a high hub portion and an extended flange portion in which the flange and hub portions of the article are developed simultaneously and in the same proportion as these portions bear in the finished article, which comprises rolling a blank of rectangular cross section with a roll having rolling surfaces disposed at right angles and causing said roll to advance, in the course of the reduction of the blank, from a predetermined point on one surface of the blank in a path defined by a straight line passing through the line of intersection of the surfaces of said blank remote from the portion being worked on by said roll. 80
  4. Process of forming a metal article having an extended flange portion, in which the flange and body portions of the article are developed simultaneously and in the same proportion as these portions bear in the finished article, which comprises applying rolling pressure to a portion only of a surface of an annular blank and causing said roll to advance continuously, in the course of the reduction of the blank, laterally as well as perpendicularly to the surface upon which pressure is being applied, and simultaneously forging the remainder of the said surface outward laterally with respect to the direction of advance of said roll. 85
  5. Process of forming annular metal articles having a high hub portion and an extended flange portion in which the flange and hub portions of the article are developed simultaneously and in the same proportion as these portions bear in the finished article, which comprises applying rolling pressure to a portion only of a surface of an annular blank and causing said roll to advance continuously, in the course of the reduction of the blank, laterally as well as perpendicularly to the surface upon which pressure is being applied, and simultaneously forging the remainder of the said surface outward laterally with respect to the direction of advance of said roll. 90
  6. Process of forming a metal article having an extended flange portion, in which the flange and body portions of the article are developed simultaneously and in the same proportion as these portions bear in the finished article, which comprises applying rolling pressure to a portion only of a surface of a blank and causing said roll to advance continuously, in the course of the reduction of the blank, laterally as well as perpendicularly to the surface upon which pressure is being applied, and simultaneously forging the remainder of the said surface outward laterally with respect to the direction of advance of said roll. 95
  7. Apparatus for rolling flanged metal articles having an extended flange portion and 100
  8. Apparatus for rolling rectangular metal articles having an extended flange portion and 105
  9. Apparatus for rolling rectangular metal articles having an extended flange portion and 110
  10. Apparatus for rolling rectangular metal articles having an extended flange portion and 115
  11. Apparatus for rolling rectangular metal articles having an extended flange portion and 120
  12. Apparatus for rolling rectangular metal articles having an extended flange portion and 125
  13. Apparatus for rolling rectangular metal articles having an extended flange portion and 130

a body portion of cross-section different from that of the said flange portion, comprising a roll having rolling surfaces intersecting in a plane substantially at right angles to the axis of rotation of said roll, means for supporting a metal blank of initially rectangular cross-section in operative relation to said roll, and means for moving said roll against a portion but not all of the surface of one side of said flange and for causing it to advance in the course of the reduction of the blank in a straight path and in a direction substantially at right angles to the axis of said roll and at an angle to said blank surface.

6. Apparatus for forming flanged metal articles, comprising a roll having rolling surfaces intersecting in a plane substantially at right angles to the axis of rotation of said roll, means for supporting an annular metal blank in operative relation to said roll, means for causing relative movement between said roll and said blank, in the course of the reduction of the blank, in a straight path and in a direction substantially at right angles to the axis of said roll, and means causing the annular blank to revolve in rolling contact with said roll.

7. Apparatus for forming flanged metal articles, comprising rolls for supporting an annular blank, a roll mounted above said blank and having rolling surfaces intersecting in a plane substantially at right angles to the axis of rotation of said roll, a roll engaging the inner surface of said annular blank, and means for adjusting the rolls to and from one another and for causing said blank to revolve in rolling engagement with said rolls.

8. Apparatus for forming flanged metal articles, comprising a roll having rolling surfaces intersecting in a plane substantially at right angles to the axis of rotation of said roll, means for causing relative movement between said roll and a blank of initially rectangular cross-section, in the course of the reduction of the blank, in a path defined by a straight line passing through the line of intersection of the surfaces of said blank remote from the portions being worked by said roll, and means for causing rolling contact between said roll and said blank.

9. Process of forming annular metal articles having a high hub portion and an extended flange portion, in which the flange and hub portions of the article are developed simultaneously in the same proportion as these portions bear in the finished articles, which comprises forming a metal blank with hub and flange portions, bringing a rolling member into contact with the intersecting surfaces of said hub and flange portions, imparting rolling pressure from said member to said blank, and causing said member to advance, in the course of the reduction of the

blank, in a substantially straight path toward the line of intersection of the planes of surfaces of said blank remote from the surfaces being worked on by said roll.

In testimony whereof, I have signed my name to this specification this 24th day of September, 1927.

ROBERT KINGSLEY HOPKINS.
